UNITED STATES PATENT OFFICE.

JOSEPH O. WALTON, OF BOSTON, MASSACHUSETTS.

SELF-LOCKING TACKLE-BLOCK.

SPECIFICATION forming part of Letters Patent No. 756,747, dated April 5, 1904.

Application filed August 12, 1903. Serial No. 169,232. (No model.)

To all whom it may concern:

Be it known that I, JOSEPH O. WALTON, a citizen of the United States, residing at Boston, in the county of Suffolk and State of Massachusetts, have invented a new and useful Improvement in Self-Locking Tackle-Blocks, of which the following is a specification.

In the patent granted me February 19, 1901, No. 668,594, I have shown and described a self-locking pulley-block in which the locking pulley or sheave was formed with a concentric groove in a plane at right angles to the axis and with a lateral extension bearing one or more cam-grooves leading off to one side into a different plane and into which the rope was led by a lateral adjustment of its free end, so as to cause the rope to be pinched and held between the cam-groove and a pinching-roller above, which latter had a stop projection on it that allowed the roller to first rotate under the initial pinching strain of the rope to avoid a scraping strain on the rope and then through the stop acting upon a stationary part of the block brought the roller to a standstill, so as to positively lock the rope with a firm hold. In connection with this form of sheave or cramping-pulley a second plain pulley was arranged beside it within the same frame and upon the same axis, but arranged to rotate independently of the cramping-pulley to accommodate the differential speed of the rope as it passes from one sheave to the opposite block and back again to the cramping-pulley. This form of block works well; but upon manipulating or overhauling the rope in the block without a load on it the rope is at times liable to catch on the locking part of the block, which causes considerable trouble and loss of time in getting it out.

My present invention consists in a simple guard combined with or formed on the block on its rear side just behind the cramping-pulley, so that the run of this part of the rope will be thrown laterally away from the cramping-face on the rear side, but will not interfere with the locking of the rope on the front side, as will be hereinafter described with reference to the drawings, in which—

Figure 1 is a front view of my patented

tackle-block with the run of the rope connecting it to a plain double block below. Fig. 2 is a rear view of the same tackle-block, showing my guard applied to the same; and Fig. 3 shows one of my tackle-blocks with a modified form of guard.

In the drawings, A represents the frame of my tackle-block, which may be made of wood, metal, or any other suitable material. It has two cells or compartments *a* and *a'*, in which upon the same axial pin P are mounted the two independently-rotating sheaves or pulleys B and B'. B is a plain concentrically-grooved sheave, while the other is wider and has a concentric grooved face B' and one or more eccentric cam-grooves B² leading out from the groove B' laterally into a different plane. These grooves B² diminish in depth as they proceed laterally from groove B' until they run out or gradually taper into the outer periphery of the sheave, so as to form cramping-faces to compress the rope between them and a superposed roller or rolling-pin C. This roller is preferably set at an incline, as shown, and has a stop projection c, which after the backlash of the rope has given an initial turn to the roller or pin C comes into stopping contact with the frame of the block and locks said pin or roller against further turning, so that it now positively locks the rope, all as set forth in my previous patent referred to.

The run of the rope in hoisting is indicated by the arrows. It passes down at 1 from my block A to the lower block D and around its sheave d. Rising on the rear side, (see Fig. 2,) it passes up at 2 to sheave B of my block. Thence passing down at 3 in front it turns around the sheave d' of the lower block D, and then rising at 4 in the rear it enters the cramping-pulley of my block and passing over it to the front terminates in the free end 5, which is in the hand of the person manipulating it. By throwing the end 5 of the rope to the right, as shown by the dotted lines in Fig. 1, and then allowing it to slacken and turn the cramping-pulley B B backward the rope is pinched and held between one of the cam-grooves B² and the locking-pin C, as before described, so that the rope 5 may now be re-

leased, and the weight hung upon the hook E of the lower block will be suspended at any desired point.

To release the rope and lower the weight, 5 the rope section 5 is first pulled in the direction of the arrow to release the clamping effect and is then swung over to the left, so as to get into the free-running groove B', and the rope 5 being then paid out runs in groove 10 B' in the opposite direction to the arrows and the weight is lowered.

The above action is effected with certainty so long as there is a considerable weight on the hook E; but it sometimes happens that the 15 lower block D is to be raised or lowered without a weight on it, as when barrels, boxes, &c., are being raised to or lowered from the upper story of a warehouse. In such case when the lower block D is to be readjusted 20 the run 4 of the rope is liable to get caught or reengage the cramping-face and remain locked between it and the pin above. To prevent this, I have provided on the rear side of my tackle-block an inclined guard G, whose 25 edge α occupies an angle that makes the cell-opening wider at the top than it is at the bottom. This causes the run 4 of the rope which is behind the pulley from the operator to have a trend always in the direction of arrow y toward 30 the concentric free-running groove B' and effectually prevents all accidental locking. The importance of this will be understood when it is remembered that the operator has 35 no control over any lateral movement of the run 4 of the rope, since it is behind both blocks, and the stiffness of the rope and the influence of the weight raised is liable to leave the upper end of section 4 of the rope with a set or bend in it that prevents it from returning to 40 the free-running groove B' unless aided by

the guard G. This guard effectually removes the difficulty and renders the block perfectly efficient and reliable in operation whether loaded or not.

In wooden blocks the guard G is conveniently formed in a separate metal plate or bar G, having a flanged and inclined edge α ; but in small blocks in which the frame is of metal it is to be cast with the frame, as seen at G' in Fig. 3. It is obvious that this same construction may be employed in larger blocks of any size.

Having thus described my invention, what I claim as new, and desire to secure by Letters Patent, is—

1. A self-locking tackle-block comprising a frame, a cramping-pulley composed of a concentrically-grooved portion and an eccentrically-grooved cam portion extended laterally therefrom, and a guard arranged on the rear 60 side of the block to throw the rope toward the free-running groove substantially as described.

2. A self-locking tackle-block comprising a frame, a cramping-pulley, and a guard arranged on the rear side to throw the rope into released position substantially as described.

3. In a self-locking tackle-block, a frame having a cell to receive the cramping-pulley, said cell having a larger opening on the rear 70 side at the top than it has at the bottom.

4. In a self-locking tackle-block, a frame having a cell to receive the cramping-pulley, said cell having on its rear side an inclined guard substantially as described.

JOSEPH O. WALTON.
